UNITED STATES PATENT OFFICE.

JAMES A. PEAPODY, OF EVANSTON, ILLINOIS, ASSIGNOR TO GENERAL RAILWAY SIGNAL COMPANY.

CONTROL MEANS FOR LIGHT SIGNALS.

Original application filed January 24, 1924, Serial No. 688,238. Divided and this application filed October 19, 1925. Serial No. 63,376.

This invention relates to railway signaling and more particularly concerns a checking or safety means for use in connection with railway signaling systems of the color 5 light type.

In the employment of multiple aspect color light signals there is always an uncertainty as to whether the signal gives an indication at all, since incandescent electric lamps are preferably used and the light of such lamps is uncertain due to the limited life of the filament, so that a signal at times may not give an indication at all. For instance, since the most common indication of 10 the signal is clear, the lamp for the clear signal unit is most apt to burn out first because it is burned more than the lamps for the other indications. If the clear lamp should burn out, no indication would be 15 given by the signal at all; and although this condition might be taken as a danger signal, it may happen that the engineer would not notice the passage of a signal location, and thereby run into a block already occupied. 20

With the above and other considerations in mind, it is proposed, in accordance with the present invention, to provide suitable automatic means whereby if a lamp burns out another lamp of equal or a more restrictive signal indication is illuminated. More 25 specifically it is proposed to have the caution lamp automatically cut into an energized circuit when the clear lamp burns out and clear traffic conditions prevail, so that a caution signal will be given instead of a 30 "dark" signal.

Other objects, purposes and characteristic features of the invention will appear as the description progresses.

In describing the invention in detail, reference will be made to the accompanying drawing, in which a single figure has been shown, being a diagrammatic view of a portion of a railway system employing multiple aspect color light signals which are controlled in a manner to automatically cut in a caution lamp when the clear lamp is burned out.

This application is a division of my co-pending application, Serial No. 688,238, filed January 24th, 1924.

Referring to the drawings, there has been shown a track to which signals embodying the present invention have been applied.

This track apparatus comprises rails 50 55 divided by insulating joints 51 into blocks in the usual manner, the block I and the adjacent ends of two other blocks H and J being shown. Each of the blocks is provided with a suitable source of energy at its exit end, which has been conventionally illustrated by the battery 52, and is provided at the entrance end with a track relay T. Since the various blocks are the same, like parts of each block will be assigned like 60 reference characters having distinctive exponents. Each of the blocks is provided with a line relay L which is energized by reason of the front contacts 53 of the track relay of the block at the entrance to which it is placed and the front contact 54 of the track relay of the block next in advance while these blocks are unoccupied. 65

Suitable multiple aspect wayside signals, 70 are located at the entrance end of each block. These signals are illustrated in a conventional manner as color light signals of the type employing incandescent electric lamps in suitable casings having distinctive color screens, usually colored green, yellow, 75 and red to represent clear, caution, and danger traffic conditions respectively. Although a particular type of wayside signal has been shown, it should be understood that any other type of color light or other wayside 80 signal in which the indication of a given traffic condition is accomplished by means of closing an electric circuit might be employed. 85

Clear indication.—Referring more particularly to the block I, the green or clear lamp G is energized under normal traffic conditions ahead through a circuit which may be traced as follows: beginning at the terminal B of a suitable source of energy which has its other 90 terminal connected to a common return wire C, front contact 55 of the track relay T, wire 56, front contact 57 of the line relay L, wires 58 and 59, winding of the check relay CR, wire 60, clear lamp G, wires 61 and 62, back 95 to the common return wire C. The energizing current for the lamp G flowing through the check relay CR is sufficient to cause this relay to assume its energized position, thereby opening its back contact 63. 100 This check relay CR may be of any desired construction, provided that it is sensitive enough to be energized by the current flow- 105

ing in the lamp G without introducing a prohibited amount of resistance in the circuit.

Caution indication.—If the block J should be occupied for any reason, the track relay T¹ assumes its de-energized position, drops its front contact 54¹, and de-energizes the line relay L. The de-energization of the line relay L causes its contact 57 to drop, thereby closing a circuit for the caution or yellow lamp Y which may be traced as follows: beginning at the terminal B, contact 57 in its lower position, wires 64 and 65, impedance unit 66, wire 67, caution lamp Y, wires 68 and 62, back to the common return wire C. It is thus noted that the caution lamp Y at the entrance to the block I is energized when the block J is occupied.

Danger indication.—If now the block I is occupied by a train, or is in danger for some other reason, the track relay T assumes its deenergized position for obvious reasons. This causes the contact 55 of the track relay T to assume its lower position, thereby closing a circuit for the red or danger lamp R which may be traced as follows: beginning at the terminal B, contact 55 of the track relay T in its lower position, wire 70, impedance unit 71, wire 72 danger lamp R, wire 73, back to the common return wire C.

Caution indication under clear conditions.—Let us assume that the block I and the block J are both unoccupied and that the relays T and T¹ assume the energized position thereby completing a circuit for the clear lamp G, as heretofore traced. Let us assume now that the clear lamp burns out so that it is extinguished and the energizing current which heretofore was flowing in the check relay CR has been interrupted. This causes the check relay CR to assume its de-energized position, thereby completing a circuit for the yellow lamp Y, which may be traced as follows: beginning at the terminal B, front contact 55 of the track relay T, wire 56, front contact 57 of the line relay L, wires 58 and 74, back contact 63 of the check relay CR, wire 75, front contact 76 of the line relay L, wires 77 and 65, impedance unit 66, wire 67, yellow lamp Y, wires 68 and 62, to the common return wire C. It is thus noted that failure of the energizing circuit for the clear lamp G, probably because the filament of this lamp has burned out, causes the caution lamp Y to be energized instead, thus giving a caution signal and allowing the engineer to proceed instead of having no signal to guide, advise or protect him against possible danger ahead.

60 The impedance units 66 and 71 have an impedance approximately equal to that of the resistance of the check relay CR. These impedance units are employed so that the incandescent lamps used in the signals G, Y, and R, respectively, may be of the same

candle power and current carrying capacity and may be interchanged if desired. It should be noted that not only failure of the filament of the lamp G causes the lamp Y to be energized instead, but that failure of the winding of the control relay CR, either because it is open or because it is shorted, causes energization of the caution lamp Y.

In the particular arrangement of track circuits shown the clear lamp G only has been protected against open circuits by the check relay CR by energizing the caution or lamp Y instead of clear lamp G. It should, however, be understood that the same arrangement may be applied to the caution lamp Y by providing a similar check relay in series with such caution lamp and providing a back contact which completes a circuit for the red lamp R when such caution lamp is deenergized; also, the same arrangement may be applied to the red lamp R by providing another auxiliary red lamp which is energized if the red lamp of the signal is burned out or its energizing circuit is open for some other reason, the same arrangement being applicable to lamp G and Y.

As already stated, the green or clear lamp being the one burning the greatest part of the time, perhaps ninety-five per cent of the time, is the lamp which is used the most and which will be the one to burn out first. If the clear or green light should burn out under clear traffic conditions, a so-called "dark" signal is the result; and while such a "dark" signal, according to the rules, signifies stop, the engineer may fail to observe the signal making it desirable to use an additional marker lamp to locate the signal. This invention provides, however, for cutting in and lighting the yellow or caution lamp whenever the green or clear lamp burns out, thereby providing a reserve indication for the green indication which not only serves the purpose of a marker light but also is more likely to assure safe control of the train. It is considered preferable to cut in the yellow or caution indication upon burning out of the green lamp, rather than cutting in a reserve lamp for the green signal, because the engineer under ordinary circumstances would observe the showing of a caution indication instead of a clear indication and would report the abnormal condition, making prompt repair more certain than if a green lamp in reserve is used. On the other hand if the signal in question is an approach signal where the yellow or caution lamp is burning almost continually it is considered preferable to have an auxiliary lamp giving the same distinctive indication when such caution lamp burns out. If desired, additional resistance may be cut in series with the yellow lamp when lighted because of failure of the green lamp, so as to give weaker caution indication and show

the engineer that something is out of order; but ordinarily the engineer would be able to detect the showing of a yellow light where a green lamp should be displayed.

5 Although the invention has been shown applied to a color light signal it is desired to be understood that it may also be applied to position light signals, where a group of lights are used to define a bar or signal 10 blade the position of which determines the signal indication.

Having thus shown one specific embodiment of the present invention and the manner in which it may be applied to one 15 particular type of trackway apparatus and associated relays, it is desired to be understood that various changes, modifications, and alterations may be made to adapt the invention to any other system and the various 20 conditions encountered in practice without departing from the spirit of the invention or the idea of means underlying the same.

What is desired to be secured by Letters 25 Patent of the United States is:—

1. A multiple aspect light signal for railroads comprising, a first light projecting unit including an incandescent lamp, a lighting circuit and control means for said lamp, a relay in said lighting circuit in series with the filament of the lamp, a second light projecting unit giving a distinctive indication different from that of the first unit, and a lighting circuit and control means for said 35 second unit which latter lighting circuit is energized independently of its control means upon de-energization of said relay provided the lighting circuit of the first unit is closed at its control means.

40 2. A light signal for railroads, comprising two light projecting units giving different signaling aspects, an incandescent lamp for each unit, a lighting circuit and control means for each lamp, and automatic means associated with the lighting circuit of one lamp for lighting the other lamp independently of its control means, said automatic means being effective whenever the lighting circuit of the first mentioned lamp is established and current fails to flow therein.

55 3. An automatic block signal system for railroads comprising, a railway track divided into blocks by insulating joints, a multiple unit color light signal at the entrance to each block including a clear light signal unit and a caution light signal unit, a circuit for said clear light signal unit including the winding of a check relay completed under clear traffic conditions ahead, a circuit for said caution signal unit completed under adverse traffic conditions ahead, and means including said check relay for independently energizing said caution signal unit.

60 4. An automatic block signal system for

railroads comprising, a railway track divided into blocks by insulating joints, a multiple unit color light signal at the entrance to each block including a clear light signal unit and a caution light signal unit, a circuit for said clear light signal unit including the winding of a check relay completed under clear traffic conditions ahead, a circuit for said caution signal unit completed under adverse traffic conditions ahead, and means including a back contact of said check relay, for energizing said caution signal unit under clear traffic conditions ahead if the filament of the lamp in the clear signal unit is burned out.

5. An automatic block signal system for railroads comprising, a railway track divided into blocks by insulating joints, a multiple unit color light signal at the entrance to each block including a clear light signal unit and a caution light signal unit, a circuit for said clear light signal unit including the winding of a check relay completed under clear traffic conditions ahead, a circuit for said caution signal unit completed under adverse traffic conditions ahead, and means for energizing the lamp of said caution signal under clear traffic conditions ahead when the check relay is deenergized.

6. In an automatic block signal system, the combination of a track divided into blocks having a track relay at the entrance to each block, a line relay, a circuit for energizing said line relay closed if the track relay of that block and the track relay of the block in advance are energized, a signal comprising a clear, a caution and a danger lamp, means for energizing said clear lamp if both the track relay and the line relay of a block are energized, for energizing said caution lamp if the track relay of a block is energized but the line relay is de-energized, and for energizing the danger lamp if the track relay is de-energized, said last mentioned means including means for energizing the caution lamp if the track relay and the line relay are both energized and the filament of the clear lamp is burned out.

7. In an automatic block signal system, the combination of a track divided into blocks each having a signal comprising a clear lamp, a caution lamp and a danger lamp, means for energizing said clear lamp of the block if that block and the next block in advance are unoccupied, energizing the caution lamp if said block is unoccupied but the block in advance is occupied, and for energizing said caution lamp if said block and the next block in advance are unoccupied and the filament of said clear lamp is burned out.

8. In a multiple unit light signal for railroads comprising, a plurality of signal lamps emitting light beams of different colors corresponding to different traffic conditions ahead, means for cutting in the lamp cor-

responding to more dangerous traffic conditions ahead if the filament of the other of said lamps fails and traffic conditions are such that it should be illuminated.

5 9. In a color light signal, two light projecting units each including an incandescent lamp and giving different signal indications when the corresponding lamp is lighted, a circuit for each lamp, a control contact in 10 one of said circuits, and a relay included in the circuit of the other lamp for closing a shunt for said control contact upon deenergization of said relay.

10. A light signal for railroads comprising, light projecting means having two incandescent lamps acting to give distinctive signaling indications corresponding to different traffic conditions when the respective lamps are lighted, a relay having contacts 20 closed upon deenergization thereof and connected in series with the filament of one of said lamps, and a lighting circuit for the other lamp including said contacts of said relay.

25 11. In a light signal, the combination with light projecting means having two incandescent lamps and giving distinctive indications when said respective lamps are lighted, and control means for separately lighting said lamps, and a relay having contacts closed upon deenergization thereof, said relay having its winding included in series with the filament of one lamp, and a circuit including the contacts of said relay for lighting 30 the other lamp independently of its control means, whereby said other lamp is automatically lighted if the first lamp fails to light when it should.

40 12. A light signal and control means therefore comprising, a plurality of light projecting units each including an incandescent lamp, a lighting circuit for each lamp, a relay having contacts closed upon deenergization thereof and having its winding included in one of said lighting circuits, a current limiting means in each of the other lighting circuits substantially equivalent to said relay winding for maintaining approximately the same magnitude of current in 45 said circuits.

50 13. In a signaling system for railroads, the combination with a multiple aspect light signal including a plurality of incandescent

lamps acting to give distinctive indications corresponding to different traffic conditions 55 when lighted, of automatic means including a relay having contacts closed upon deenergization thereof for lighting the lamp giving a more restrictive indication whenever the lamp giving a more favorable indication fails to light when it should.

14. A multiple aspect signal, a circuit and control means for each signal aspect, and automatic means associated with the circuit of one aspect for energizing the circuit 65 of another aspect independently of its control means, said automatic means being effective whenever the circuit for the one aspect is established and current fails to flow therein.

70 15. A multiple aspect signal, giving indications of different restrictions, a circuit and control means for each signal aspect, an automatic means associated with the circuit of a less restrictive aspect for energizing the circuit of a more restrictive aspect independently of its control means, said automatic means being effective whenever the circuit for the less restrictive aspect is 75 established and current fails to flow therein.

16. A multiple aspect light signal for railroads having lamps controlled according to traffic conditions ahead, and automatic means independent of traffic conditions, for lighting a second lamp after a first lamp 85 fails and traffic conditions are such that the first lamp should be lighted.

90 17. A multiple aspect light signal for railroads having lamps controlled according to traffic conditions ahead, and automatic means, independent of traffic conditions, for lighting a more restrictive lamp if a less restrictive lamp fails and traffic conditions are such that the less restrictive lamp should 95 be lighted.

100 18. A multiple aspect light signal for railroads having lamps controlled according to traffic conditions ahead, and giving yellow and green indications respectively, and automatic means, independent of traffic conditions, for lighting the yellow lamp if the green lamp fails and traffic conditions are such that the green lamp should be lighted.

In testimony whereof I affix my signature.

JAMES A. PEABODY.
